IMITATION POCKET HANDKERCHIEF

Donald A. Ripple, San Francisco, Calif.

Application October 17, 1947, Serial No. 780,467

1 Claim. (Cl. 2—279)

1

This invention relates to an improved imitation pocket handkerchief and has particular reference to a unique article that is adapted to fit in the lapel pocket of a coat or other garment, the primary object of the invention being to construct the article in a form resembling a folded handkerchief with the pointed tips extending from the pocket.

Regular men's handkerchiefs are often folded in a pleasing manner and inserted in the lapel pocket of the man's coat with the folded tips extending therefrom and are intended for decorative purposes rather than for use. Handkerchiefs folded in that manner often get disarranged and thus lose their decorative ness.

An important object of the present invention is to construct the decorative article by making triangular segments from straight strips of material that is first hemmed along both edges, after which the segments are folded and secured to a suitable form of heavy paper or thin cardboard that is adapted to fit in the lapel pocket of a man's coat in a manner enabling the tips of the decorative folded segments to extend above the pocket and resemble a folded handkerchief.

Another object of the present invention is to secure the said folded segments to the upper portion of the paper or cardboard form by stitching the same thereto and to provide an adhesive strip of material over the stitching and around the upper portion of the cardboard.

A further object of the present invention is to provide a unique pocket decorative article that is durable, practical, simple in construction, economical to manufacture and highly serviceable in use.

Other objects and advantages will be apparent during the course of the following description.

In the accompanying drawing forming a part of the specification wherein for the purpose of illustration like numerals designate like parts throughout the same.

Fig. 1 is a plan view of a strip of hemmed material from which the triangular segments are formed.

Fig. 2 is a plan view of one of the triangular segments.

Fig. 3 is a side elevational view of one of the imitation handkerchief pocket articles showing two tips stitched to the card and the stitching covered with an adhesive tape.

Fig. 4 is an enlarged side elevational view similar to Fig. 3, except showing three tips projecting above the card, and

Fig. 5 is a vertical sectional view taken on line 55

2

5—5 of Fig. 4, looking in direction of the arrows.

Referring in detail to the drawing and the numerals thereof, the numeral 6 in Fig. 1 designates an elongated strip of linen or other suitable handkerchief material, both edges of which are hemmed as at 7 and 8, respectively. The angularly extending dotted lines 9 indicate how the said strip 6 is cut to form the triangular segments 10 shown to advantage in Fig. 2, the dot and dash line 11 indicating the folding line for each of the segments. The base member 12 is suitably formed to fit in the lapel pocket of a man's coat and is preferably made of heavy paper or light cardboard, sometimes called tagboard. The segments are folded on the said line 11, forming the tips 13, which tips are positioned on the upper portion of the base member 12 and stitched thereto as indicated at 14 in Fig. 3 and are arranged to resemble a folded handkerchief.

20 An adhesive strip 15 made of cloth or any other suitable material is placed over the said stitching 14 and is adhesively secured all around the top portion of the said base member. The said adhesive strip 15 serves three distinct purposes; first, it seals the stitching 14 in a manner making it impossible for the stitched threads to get loose; second, it reinforces the top portion of the base member 12 and third, it provides a binder and greatly assists in securing the triangular tips to the base member.

From the foregoing description taken in conjunction with the accompanying drawing it is obvious that the present invention provides a unique article of manufacture in which the cost is reduced to the minimum. The method of making the triangular segments from straight strips of hemmed material prevents any waste of the same, and that feature together with the method of folding and securing the triangular tips to the tagboard or paper base member by a line of stitching and a strip of adhesive material produces an exceptionally low cost finished product in a most neat and decorative manner. The base member provides an excellent writing surface for making notes, etc. and may have printed advertising matter thereon if desired.

It is to be understood that the form of my invention herewith shown and described is to be taken as a preferred example of the same and that various changes relative to the material, size, shape and arrangement of parts may be resorted to without departing from the spirit of the invention or the scope of the subjoined claim.

Having thus described by invention, I claim:
 An imitation pocket handkerchief of the character described comprising a base member made of fibrous material and adapted to fit in the lapel pocket of a coat, a plurality of folded triangular segments positioned across the upper portion of the base member and extending above the same, the said triangular segments being arranged to resemble the tip portions of a folded handkerchief, a line of stitching securing the 10 folded triangular segments to the base member, and a strip of flexible adhesive material positioned over the said line of stitching and across the upper portion of the base member, whereby the stitching is sealed, the said strip of adhesive 15

material additionally securing the folded triangular segments to the base member.

DONALD A. RIPPLE.
